STENCIL PRINTING MACHINE

Josef Kessel, Krefeld, Germany

Application May 2, 1938, Serial No. 205,479
In Germany September 10, 1936

13 Claims. (Cl. 101—123)

5 Stencil printing machines are known with intermittently travelling printing supports and with arrangement for automatically lifting and lowering the stencils and for moving the doctors to and fro.

The invention has for its object to carry out automatically all operations necessary for the printing of webs and the like. This object is attained according to the invention in that the 10 laterally unshiftable and unstretchable printing support provided with a heating device, a heated pasting and washing device is driven by a suitable continuously running motor and controlled by a gear and two clutches at two different speeds whose change over from rapid speed to creeping speed is effected by a catch which clamps the support and during the forward travel thereof successively disengages the clutch for rapid speed, engages and disengages 15 the clutch for creeping speed and actuates a fine adjusting device which indicates the register position and releases the catch for the return movement and engages in the drive of the machine an auxiliary motor which imparts a half revolution to a toothed wheel and a switch 20 disc connected therewith and thus lowers the stencils on to the web, and switches on another auxiliary motor which actuates a doctor mechanism and again switches on the motor for raising 25 the stencils, which last mentioned motor effects the engagement of the rapid speed clutch and the clamping of the catch on the printing support.

An embodiment of the invention is illustrated 30 by way of example in the accompanying drawings, in which:

Fig. 1 is an elevation of the machine viewed from the gearing side.

Fig. 2 shows the pasting arrangement of the 40 machine in top plan view.

Fig. 3 is a top plan view of the gear with fine adjustment device.

Fig. 4 is a vertical central section through the pasting arrangement.

Fig. 5 shows in front elevation the gearing and the raising and lowering device for the 45 stencils.

Fig. 6 is a top plan view of the doctor mechanism,

Fig. 7 shows the doctor reversing mechanism in side elevation,

Fig. 8 is a top plan view of Fig. 7,

Fig. 9 shows the fine adjustment device in top plan view,

Fig. 10 is a side elevation of Fig. 9,

Fig. 11 is a top plan view of the front end of a stencil,

Fig. 12 is a side elevation of Fig. 11,

Fig. 13 shows the lay out of the machine for electric drive.

The stencil printing machine comprises substantially a printing table covered with felt and adapted to be heated from below, around which table an endless band 2 of rubber, rubberized fabric or the like circulates in the longitudinal direction of the table and is moved in longitudinal direction towards a roll 3 by rolls 3 and 4 mounted on the short ends of the printing table 1. The roll 3 is keyed on the driving shaft 5 of the machine to which the rotary motions of a driving motor A are transmitted through the intermediary of a gearing arrangement B for full or semi-automatic operation. A pasting arrangement I is arranged adjacent the roll 4 for automatically applying paste and above the printing table stencils 6 are arranged which in conjunction with a doctor mechanism II serve for printing the web 7 of smooth or rough fabric or paper or other material running off a roll. Below the printing table 1 there is a washing arrangement III through which the lower side of the band 2 passes to be automatically freed from paste, printing ink or the like adhering to its surface. The printing table 1, is composed of several plates adapted to be fitted together, supported by girders 8 and closed at the sides, and is closed from below like a box by the lower side of the band. A heating arrangement 9 in this table is constructed as an automatic hot air, steam or electric heating arrangement, or the like, or may be connected to a central heating system and so installed, that the heating medium passes not only through the printing table but also through a pressure cylinder 10 for pressing the web 7 to be printed against the pasted printing support 2, the washing arrangement III and the drying device IV for the printed web.

The heat radiated by the printing table and the pressure cylinder 10 is utilized for pasting on the web 7. To enable the web to be fixed on the printing support 2 in stretched condition as little paste as possible is applied on the support 2 in stripes 11 by a ribbed cylinder 12 (Fig. 2). This cylinder 12, which is composed of parts which rest loosely between the printing support 2 and a paste feeding roll dipping into the paste box 13 and connected by toothed gear wheels with the roll 4, is guided laterally only by adjustable levers 15, and is rotated by friction by the movement of the printing support and the 55

roll 14. The ribs of the body 12 are preferably so narrow and spaced so far apart that the paste stripes 11 applied to the printing support 2 do not contact after being rolled out. In the pasting arrangement I a squeezing cylinder 16 is also arranged which is adjustable in its bearings and prevents the roll 14 from taking up too much or too little paste. As paste, dextrine has for example been found suitable, as it becomes glass-hard when dried by heat, but rapidly re-dissolves in warm water, so that it is possible to remove it without difficulty from the printing support in the washing arrangement III. On the other hand the rolled-on paste only penetrates slightly into the fabric and thus keeps the fabric in a state perfectly capable of taking up ink.

Above the pasting arrangement I adjusting levers 17 and guide plates 18 are arranged at the two sides of the band 2, the plates 18 having flaps 19 extending vertically downwards and bearing against the edges of the band, so that the band 2 is positively guided on to the printing table in the correct position. The band 2 runs along the printing table without clearance between two guide bars 20 fixed at the sides of the printing table, and from these bars 20 a resilient holding down element 21, for example a thin sheet metal, rubber, reinforced fabric strip or the like, extends across the printing support so that the latter is enclosed as in a groove. The two guide plates 19 exert a resilient pressure on the yieldable band also from above and facilitate its passage on to the printing table by pushing the band inwards. Guide rollers or similar means might be employed instead of guide plates. The printing support is preferably supported in the gap between the roll 4 and the printing table 1 by a transverse support 22. The positive lateral guiding of the upper side of the band counteracts diagonal and lateral displacements thereof which may be caused by the band structure, heating and cooling, and so forth, so that the printing support 2 circulates with its central longitudinal axis exactly in register with the longitudinal axis of the printing table. A uniform running of the printing support is also ensured in that the feed and guide rolls 3 and 4 are interconnected by a stretchable driving chain 23 which runs over the driving shaft 5 of the machine.

The film printing stencils 6 required for the printing are mounted on a pair of rigidly interconnected vertically shiftable bars 24 arranged parallel to the printing support 2, this pair of bars being guided with frictional contact by guide rods 25 in one or more guides 26 mounted vertically on the printing table 1, so that longitudinal and lateral displacements of the pair of bars 24 cannot occur and consequently in the case of multicolour printing the stencils are always accurately in register the one above the other. The raising and lowering of the stencils takes place when the printing support 2 is at a standstill and is effected by a lever 27 which is constructed as a bell crank lever and actuated by hand. The lever 27 is connected by a connecting rod 28 with a lever system 29 by whose movements the pair of bars 24 and consequently the stencils 6 are moved up and down. A second rod 30 connects the lever 27 with a crank disc 31 of the motor C, so that the stencils 6 can also be raised and lowered by motive power. The stencils 6 are fixed by front and rear riders 32 and 33, adapted to be clamped on the two bars 24. The front riders 32 engage behind abutment bolts 34 mounted on the longitudinal sides of the stencils and press

the stencils by clamping screws 35 with hand operable head against the front bar serving at the same time as abutment bar for the pressure table I. Thus, the front end of the stencil is unshiftably fixed in the longitudinal and transverse direction of the printing table. In order that also the rear end of the stencil cannot shift laterally, the rear riders 33 are constructed as lateral stops between which the stencil is stretched. On one of the narrow sides of the stencils there is an abutment bolt 36, by means of which any turning of the stencil around the vertical axis can be noticed and its lateral fitting is rendered possible. The number of stencils to be fixed depends upon the number of colours to be printed and may vary within limits as desired. In the example described and illustrated two stencils are provided, each stencil prints a separate color, and the second stencil prints over the first. By employing stencils correctly cut according to color, a large range of shades can be produced with only three or four stencils, and the length of the printing table can be relatively short. A great number of stencils with which only one colour can be printed are necessary for producing a multicolour print and consequently require a machine of relatively long construction, in which case merely the printing table with printing support requires to be changed, whereas the two head ends of the machine remain unchanged. The machine may also be of a width, to allow the printing of wide webs or single pieces such as table cloths, or the like in a single process.

The printing, which takes place when the printing support is at a standstill and the stencils are lowered, is effected either by means of the automatically operating doctor mechanism II or by hand by moving the printing ink backwards and forwards on the stencils 6. In the case of automatic operation the printing ink is spread by means of a spreader or doctor through the stencils on to the web 1 which is moved to and fro by a motor D independent from the motor C. In the case of hand operation, the doctors are moved to and fro by hand. The latter method only comes into question, when stencils with coarse and fine patterns are used at the same time, or when little ink is required at one portion of a print section and a lot of ink at another portion. The heat radiated by the printing table exerts a favourable effect on the printing operation in that the ink after being applied on to the web at the same time gives up moisture, which deposits on the open portions of the stencils with a gauze ground, whereby the printing ink is continually maintained in soft condition and the meshes in the pattern of the stencil are kept open. Thus, it is possible to print without interruption, or to wash out the stencils only when the service is stopped for a relatively long time, for example, over night. After the printing operation the stencils 6 are raised automatically by the lever 27 or by hand, whereupon the printing operation is terminated. The printed web 1 then passes at the next feed into the drying arrangement IV into which it is drawn by means of a winding cylinder 38 on which an end strip 39 connected with the beginning of the web 1 is fixed. The winding cylinder 38 is driven by a belt 40 or the like through the intermediary of the driving shaft 5 of the machine. A driving shaft not shown may be mounted in the bearings of the winding cylinder 38 instead of this cylinder, and this shaft drives a mechanism by which the finished material is run out of the 75

drying arrangement IV, to a folding and collecting device.

While a length of web 1 equal to the length of a repeat is being pulled off the printing support 2, the lower side of the band 2 moves through the washing arrangement III. This arrangement comprises a vessel 41, through which a heating medium passes, rotary brushes 42 dipping into the water in the vessel, laterally shiftable stricklers 43 arranged under the printing support and counter pressure rollers 44 mounted above the printing support 2 and the stricklers 43, by which elements any paste softened by the warm water while the printing support is standing still, and also ink smears, are washed and scraped off the support as it is moved on. The brushes 42 and stricklers 43 receive their drive from a gear B through the intermediary of a chain drive or the like and a rod system 43a actuated by a grooved cam 43b on the end of the shaft 5. The cleansed printing support 2 is stretched on its travel to the pasting arrangement I by a stretching roller 46 and dried by the heat radiated downwards from the printing table.

If the support 2 is fed at a low speed the output of the machine will be too small, and if it is fed at a high speed the impetus will be too great at the end of the feed to ensure accurate registering. Consequently the band must run at a high speed at the commencement of its feed and be slowed down so that it moves into its extreme end position at a creeping speed.

The feed of the printing support 2 from one printing position to the next may be produced by the motor A or by hand. The motor A is connected with the driving shaft 5 by the gear B which can be alternately engaged and disengaged by electric clutches E and F or by a hand-actuated clutch G. The clutches E and F serve to quickly and slowly move the printing support 2 in the case of electric drive, and the clutch G, which is only actuated when the clutches E and F are currentless, serves for the quick movement and, in combination with a brake H, for the creeping movement, whereas a hand wheel J mounted on the countershaft 47 of the gear B makes it possible to move the printing support 2 by hand.

The operation of the clutch G is conditional upon the raising and lowering of the stencils 6 and the doctoring of the printing ink being carried out by hand, and the motors C and D, and all other electric elements of the machine, with the exception of the motor A, being cut out. The pulley 48 connected to a belt with the shaft of the motor A first runs idle when the motor A is switched on. When a hand lever 51 fixed on the end of a shaft 50 is turned, a cam disc 49 turns about the axis of this shaft, axially shifts a spring brake or the like towards the pulley 48 by depressing a clutch lever 52 oscillatable about a fixed point, and thus couples this pulley with the counter shaft 47, thus causing the feed of the printing support 2 at high speed through the intermediary of the wheels 53, 54, 55, 56 of the gear B, which produce a reduction of the speed of rotation of the motor shaft. When the hand lever 51 is swung back, the clutch G is disengaged again and at the same time the cheek brake H is applied and the printing support stopped. The cheek brake H is arranged in the gear wheel 56 forming a casing and mounted on the driving shaft 5, and is actuated by a cam 57 controlled by a cam disc 58 arranged on the rear end of the control shaft 50. The rotation of the counter

shaft 5 can then be carried out by hand by the hand wheel J, in order to attain particularly fine adjustments of the printing support in its repeat position.

Manual adjustments, which are necessary in the case of semi-automatic service, are carried out with the aid of a fine adjusting device K which comprises a magnifying indicating device, consisting for example of a bipartite, unequal armed indicator 59, 60, whose short arm 59 is oscillated through a small angle by the contact with a catch L adapted to be clamped on the printing support 2, whereas the arm 60 connected with the short arm 59 by intermeshing teeth, swings out against the action of a spring 15 through an angle many times greater than that of the deflection of arm 59 until it strikes against an adjustable electric contact 61 or the like by which the feed of the printing support is very accurately limited and optically or acoustically 20 indicated or, in the case of electric drive, one or several electric switches are actuated which will be hereinafter described.

The catch L, which has a clamping plate 63 adapted to be clamped on the printing support 2 electromagnetically or by hand with the aid of a removable lever 62, is pushed back by hand or mechanically up to a stop 64 adjustably fitted in the initial position or to the beginning of the repeat when the printing support reaches its extreme end position. The mechanical return of catch L is effected by a screw spindle 65 which extends through the catch and is continually rotated by a transmission gear 66 connected with the motor A. A pin 68 is loosely passed through 35 a hole in the catch or through a hollow magnet 67 thereof after the catch has been unclamped, which pin engages in the groove in the screw spindle and effects the return movement of the catch L. Before the printing support receives 40 a fresh movement, the pin 68 is removed and the catch L again clamped in position, whereupon it is carried along until it encounters the short lever arm 59 of the fine adjusting device K. By turning the hand wheel J the fine adjusting device allows the smallest movements of the printing support to be read, so that it can be adjusted absolutely in register below the stencils 6 which are in the raised position.

When the printing support 2 has been adjusted, the stencils 6 are lowered by means of the two armed lever 27, whereupon the printing ink is distributed on the web 1 mechanically or by hand through the stencils. After the printing ink has been stirred the stencils are again raised 55 by means of the two armed lever 27.

In the case of electric drive the motors A, C and D become operative in succession. The three motors are connected to a common supply main M and, like the other driving means of the stencil printing machine, they can be switched on and off alternately or partly simultaneously by switches a, b, c, d, e, f, connected up in a low or high tension circuit N, and thus effect the uninterrupted drive of the machine. The clutch 60 G and brake H are disengaged during the electric drive and the lever 62 of the catch L is removed, so that the catch can now be electrically clamped on the printing support 2 and mechanically returned by the screw spindle 65. This 65 screw spindle only serves for the idle return of the catch, but rotates continually. A belt 65a extends from the shaft 12 of the transmission gear 66 to a shaft 65b on which a bevel wheel 65c is mounted which permanently meshes with 70 75

a bevel wheel 65d on the screw spindle. The electric clutches E and F in the gear B and the electromagnets 67 and 69 in the catch L now become operative which have been switched in by the switches a—f of the plant. The clutches E and F effect successively the quick and slow rotation of the driving shaft 5 of the machine and consequently the quick or creeping feed of the printing support 2. The counter shaft 47 carries a second pulley 70 with the clutch E and a third pulley 71 with the clutch F. The pulley 70 is directly connected with the shaft of the motor A by a belt and the pulley 71 with the shaft 72 of the transmission gear 66 also by a belt. Both pulleys 70 and 71 first run idle. When the clutch E is engaged, that is the pulley 70 is coupled with the counter shaft 47, the printing support 2 moves forward at high speed through the intermediary of the wheels 53, 54, 55, 56 of gear B. If the clutch F is engaged and the pulley 71 coupled with the counter shaft 47, the number of revolutions of this counter shaft is reduced by the reduction gear 66 so far, that the printing support is moved by the gear wheels 53, 54, 55, 56 only at a creeping pace into its extreme repeat position, which is determined by the fine adjusting device K, whereas in the case of hand operated driving shaft 5 the extreme repeat position of the printing support, as stated, is only indicated magnified by the deflection of the indicator 60 up to the electric contact 61. At the same time when the printing support 2 comes to a standstill, in the case of electric drive, the electromagnets 67 and 69 of the catch L and the clutch F are rendered currentless and the circuit of the motor C is closed by the indicator board contact 60, 61. When the clutches E and F are now disengaged whereas the motor C is started, the clamping plate 63 of the catch L is loosened and the pin 68 remaining permanently in the aperture of the hollow magnet 67 is caused to drop, and thus effects the return of catch L through the intermediary of the screw spindle 65. The screw spindle has at one end an annular groove 73 into which the pin 68 glides when the catch is in its initial position, and is held in this groove until the magnet 67 is reexerted. The annular groove 73 and the abutment 64 allow the catch to pass into the initial position at the same height. During this time the motor C, which participates in the electric controls by means of a switch disc 74 connected with the crank disc 31, effects the lowering of the stencils 6 by a half-revolution. A pinion 75 on the shaft of the motor C transmits the rotations of the shaft to the crank disc 31 constructed as a spur wheel and connected with the stencil holding bars 24 by the lever system 30, 27, 28, 29. The half revolution of the crank disc 31 is automatically controlled by switches a—f of the plant and by the control disc 74 over which the motor C is automatically switched out after the lowering of the stencils. The stencils being lowered, the switched off motor C effects through the switch disc 74 and switches a—f of the plant the switching in of the motor D, which actuates the doctor device II for distributing the printing ink through the stencils on to the web 1. The doctor device II (see Figs. 1 and 6) consists of two endless pulling elements for example chains 77, driven by a chain 77a through the intermediary of a shaft 77b (Fig. 6). The chains 77 carry a cam 78 and a bolt 79. This bolt 79 circulates with the chains 77 about the axles of

this driving wheel and moves a carriage 80 to and fro, whereas the cam 78, in circulating with the chains 77, feeds the control disc 81 through a part revolution. This control disc 81 has contacts 82 arranged in star shape which are brought into contact with a spring 83, thereby closing one of the switches a—f and stopping the motor D. The ends of a pull rope 84 are connected to the ends of the carriage 80, so that this rope constitutes an endless pulling means. This pull rope is guided over pulleys 87 in such a manner that it extends across the printing table at three points as a double pulling rope, one of whose sides always runs in the direction in which the pulling element moves. A doctor holder is rigidly connected to similarly moving sections of this pulling rope and is consequently moved to and fro across the table in synchronism with the to and fro motion of the carriage. The stencils 6, adjusted and fixed according to register 20 over the printing support by front and rear abutment means 32 and 33 lie between the outer guide bars 86 with guide or rope pulleys arranged on their ends. A third guide bar 88 is preferably provided between the stencils and also carries 25 a guide pulley so that the pulling element extends from one end of the carriage 80 and is guided several times across the printing table between the end guide bars 86 before reaching the other end of the carriage 80. The doctor 30 holder 85 is carried at each end by a vertically shiftable spring bolt 89 mounted in a carriage 90 (Figs. 7 and 8) and provided with a roller 93 resting on a cam bar 91 slidable along the end guide bars 86, 88 between abutments 92. 35 Each cam bar 91 has two abutments 94, one at each end. As the doctor holder 85 moves to and fro, it shifts the cam bars 91 by means of the bolts 89 whose rollers 93 bear against the abutments 94 at the front end of the cam bars 91 40 in the direction of movement. At the reversal of the doctor holder 85 the cam bars 91 first remain stationary and the rollers 93 run along the cam race thereof and vertically shift the spring bolts 89, before reaching the abutments 94 at the actually inner end of the cam bars, whereupon these cam bars are shifted to the abutment at the other end of the guide bars 86, 88 where, at the reversal of the doctor holder 85 the operation is repeated. The doctor holder 50 85 is carried by the bars 24 and consequently ascends and descends with the stencils. The doctor holder 85 consists of a bar with longitudinal slots 95 in which the doctors 37 loaded by weights are inserted from above and rest on 55 the stencils 6 by their specific gravity, so that the doctors push before them the heap of ink placed on the stencil by hand or by means of a re-filling apparatus in the direction in which the doctor holder is moved. At the ends of the 60 guide bars 86, 88 the doctors 37 slip, through the intermediary of their holder 85 and the cams 91, to behind the heap of ink and push it before them in the opposite direction as the doctor holder continues its movement. The number of 65 to and fro motions can be regulated by the switch disc 81 which switches off the motor D either the first time the cam 78 contacts or only after it has contacted several times. The contacts 82 of the switch disc 81 may be either adjustable 70 or unadjustable, or can be separately adjusted for each kind of movement. When the advancing cam 80 contacts with one of the abutments of the switch disc 81, of which as many are provided as there are contacts 82, it moves the switch 75

disc 81 through one twelfth of a revolution. The motor D is therefore stopped after a single to and fro movement of the doctor holder 85. If two cams 78 are arranged on the catch chain 5 spaced at a certain distance, the motor D is stopped after a single to or fro motion. If, however, there is only one cam on the chain 77 and six or less contacts 82 are provided on the switch disc 81, in the case of twelve abutments, 10 the contact spring 83 only comes into contact with a contact 82 after the cam 78 has circulated two or more times, so that the motor D is cut out only after the doctors have performed two or more reciprocating movements.

15 After sufficient doctoring or after the motor D is cut out, the motor C is again connected in the circuit through the switch disc 74 and switches a-f of the plant so that after the shaft of the motor has performed another half revolution 20 lifts the stencils and at the same time closes the circuit of the catch magnets 67, 69 and of clutch F. The pin 68 is thus drawn into the hollow magnet, that of the catch L is unlocked, the clamping plate 63 is clamped on the printing 25 support 2 and the catch advanced by the printing support 2 which is fed at high-speed through the clutch E. Just in advance of the fine adjusting device K a travel stop 97 is arranged with two contact levers 98 and 99, which stop 30 is laid down by the advancing catch L against the action of a spring 100, and through the intermediary of contacts 101 and 102, successively actuates two of the electric switches a-f by which the disengagement of the clutch E and 35 a moment later the engagement of the clutch F is effected. As soon as the printing support has arrived at the end of the repeat feed, the catch L knocks over the lever 59 of the fine adjusting device K which swings the pointer 60 up to the 40 contact 61, whereby through the intermediary of three switches of the plant a-f the circuit of the clutch F is opened and at the same time the circuit of the catch magnets 67, 69 and of the motor C is closed.

45 The electric drive of the machine takes place in the following manner: First the main switches 103 and 104 of the supply mains M and the secondary circuit N are closed and the main driving motor A is switched on by closing the circuit by a press button switch 105 or the like, the driving shaft 5 being declutched. Current then flows through the wire 106 across the press button switch 105, a protecting device g series connected with the motor A and whose switch is closed and conducts the current through the return wire 107 to the mains M and through the wire 108 to the motor A and thence over the return wire 17 back to the mains M. It is supposed that the catch L has turned over the lever 59 of the fine adjusting device K. Across the pointer 60 and contact 61 of this device the switches e and f of the secondary circuit N are opened, the magnets 67 and 69 of the catch L and the creeping motion clutch F are rendered currentless and at the same time the switch d is closed and the gear motor C is switched on and now effects the lowering of the stencils 6. When the circuit is closed by the pointer 60 and the contact 61, the current flows along the following path: source of current 109, feed wire 110, pointer 60, contact 61 of the fine adjusting device K, wire 129, switch f which is opened, return wire 111, switch e which is likewise opened, return wire 111, switch d which is closed, return wire 111 to source of current 109. The mains

current flows over the closed switch d along the following path: feed wire 106, closed switch d, wire 112, relay i, whose switch is closed over the return wire 107, wire 130, gear motor C, return wire 107 to the mains M. Whilst the gear motor C is running the spur wheel 31 performs a half revolution, whereupon two friction contacts 113, 114 arranged on the periphery of the switch disc 74 connected with the spur wheel 31 open the switch d and close the switch c by contacting with the contact 131 of the switch disc 74, and thus open the mains circuit of the gear motor C and close that of the gear motor D for the doctoring. After the spur wheel has performed 10 half a revolution the secondary current flows 15 along the following path: source of current 109, feed wire 110, spring contact 131 of spur wheel 31, friction contacts 113, 114 and their wires 115, 116, switch d, which is opened, return wire 111, switch c, which is closed, return wire 111, source 20 of current 109. By the opened switch d the switch of the relay i series connected with the motor C is opened and this motor C stopped. By the closed switch c the switch of a relay h 25 series-connected with the motor D is closed and the doctor motor D switched on. As the doctor motor D rotates the mains circuit is as follows: feed wire 106, switch c, wire 117, relay h, which is kept closed over the return wire 107, wire 118, doctor motor D, return wire 107. After sufficient 30 doctoring with the doctor device II has been done the doctor motor D is stopped again by the star switch 81. The secondary circuit then flows along the following path: source of current 109, feed wire 110, contact spring 83, star 35 contact 82, wire 119, switch c, which is opened, wire 111, switch b which is closed, returned through 111, source of current 109. By the opening of the switch c the relay h is also opened and the doctor motor D stopped. By the closing 40 of switch b the relay i is closed and the gear motor C restarted. The motor C receives its current from the mains M through feed wire 106, switch b, wire 112, relay i which is held closed over the return wire 107, wire 130, motor 45 C, return wire 107, mains M. The motor C now running again rotates the spur wheel 31 through half a revolution with the result that the stencils 6 are raised. In this raised position the motor C is again switched off by the switch disc 50 74 and at the same time the magnets 67, 69 of the catch L receive mains current over the switch f and the clutch E for the quick forward movement of the printing support 2 through the switch a. The secondary current then flows 55 from the source of current 109 through wire 110, spring contact 131, friction contacts 114, 120, 121, their wires 116, 122, 123, switch f which is closed, wire 111, switch b which is opened, wire 111, switch a, which is closed, back through 60 wire 111, source of current 109. The current now flows from the mains through the feed wire 106, switch f and switch a, wire 124, magnets 67, 69 of the catch L, return wire 107 and wire 125, clutch E for the quick feed movements of 65 the printing support 2, back through wire 107 to the mains M. The clutch L under current clamps tightly on the printing support 2 by which it is moved forward with the aid of the clutch E. The oncoming catch L knocks over the abutment 97 arranged in the path of the printing support 2 and by means of its contacts 98, 99 successively closes two spring contacts 101, 102 the first of which 101 breaks the circuit of the clutch E for the high-speed, whereas the second 70 75

contact 102 closes a moment later the circuit of the clutch F for the creeping speed. The opening and closing of the circuits of both clutches E and F is effected again over the switches e and d. The secondary circuit extends as follows: source of current 109, wire 110, path contact 98, contact spring 101, its wire 126, switch a which is opened and a moment later source of current 109, wire 110, path contact 99, contact spring 102, its wire 127, switch c which is closed, back through wire 111, source of current 109. From the mains wire M the current now flows through the feed wire 106, switch e, wire 128, clutch F for the creeping speed, return wire 107. The printing support 2 now brings the catch L at creeping speed up to the second abutment lever 59 which is also knocked over and thus oscillates the hand 60 of the fine adjusting device K, which movement is considerably magnified so that the end of this hand brushes over the contact 61, whereby the switches d, e, f in the secondary circuit 110, 111 are simultaneously actuated, so that the mains circuit M of the creeping motion clutch F and of the magnets 67, 69 of the catch L are opened and that of the gear motor C is closed for the purpose of lowering the stencils 6. The sequence of operations then commences afresh. By switching off the motor A by the press button switch 97 the machine is brought to a standstill. Clutches may be employed instead of the auxiliary motors C and D which clutches may also be controlled by switches similar to the switches a—f, so that all movements of the machine can be controlled by a single driving motor.

I claim:

1. An electric stencil printing machine comprising in combination an intermittently travelling laterally unshiftable and unstretchable printing support, stencils arranged above said support, a device for heating said support, heated printing and washing devices, a continuously rotating motor, a controlled gear between said motor and said support, two clutches one for rapid speed and the other for creeping speed, a catch adapted to clamp on said support during the forward motion of said support to successively disengage the clutch for rapid speed, engage and disengage the clutch for creeping speed, a fine adjusting device for indicating the register position and actuated by said catch and adapted to release said catch for the return movement, an auxiliary motor controlled by said device, a toothed wheel adapted to be rotated through half a revolution by said auxiliary motor, a switch disc connected to said toothed wheel adapted to lower said stencils, a second auxiliary motor controlled by said disc, a doctor mechanism above said support moved to and fro by said second auxiliary motor, said second auxiliary motor adapted to again switch on said auxiliary motor to raise said stencils and engage the clutch for rapid speed and clamp said clutch on said printing support.
2. In a stencil printing machine as specified in claim 1, the fine adjusting device comprising an indicator indicating on a larger scale and having two arms of different lengths, the short arm constituting the lever and being deflected a short distance by the impact of the catch on the printing support, intermeshing teeth connecting the short arm to the long arm constituting the pointer and adapted to transmit the movement of said short arm to said long arm, the contact in the path of movement of said long arm being ad-

justable to accurately determine and indicate the feed of said printing support.

3. In a stencil printing machine as specified in claim 1, means for returning the catch from its end position into its initial position, said means comprising a screw spindle driven by the main driving motor, a pin in said catch adapted to engage in the thread of said screw spindle, and a magnet adapted to hold said pin in raised inoperative position, said magnet rendered currentless with that of the catch when the catch reaches its end position.

4. In a stencil printing machine as specified in claim 1, means for returning the catch from its end position into its initial position, said means comprising a screw spindle driven by the main driving motor, a pin in said catch adapted to engage in the thread of said screw spindle, and a magnet adapted to hold said pin in raised inoperative position, said magnet rendered currentless with that of the catch when the catch reaches its end position, said spindle having an annular groove in which the pin and consequently the catch are held in their initial positions until their magnets are again excited.

5. A stencil printing machine as specified in claim 1, in which the doctoring device comprises a motor-actuated pull aggregate, at least one pin in said pull aggregate, an anchor bolt in said pull aggregate, a carriage mounted on said bolt, a pull rope fixed at both ends to said carriage, a plurality of pulleys continually guiding said rope on a tortuous path, and a doctor holder attached to several sections of said rope moving in the same direction.

6. A stencil printing machine as specified in claim 1, in which the doctoring device comprises guide bars, a carriage shiftable on said guide bars, vertical pins resiliently mounted on said carriage, a doctor holder vertically shiftable on said pins, cam races slidable at the side of said carriage, rollers supporting said doctor holder on said cam races, doctors mounted on said holders, abutments at the ends of said guide bars, cam noses at their ends, and a nose ascending towards the middle, said noses adapted to cooperate with said abutments to transport said doctor holder into its extreme positions and in each of these positions to raise said holder and bring the doctors behind the heap of ink on the stencils.

7. A stencil printing machine as specified in claim 1, in which the doctoring device comprises a motor-actuated pull aggregate at least one pin in said pull aggregate, an anchor bolt in said pull aggregate, a carriage mounted on said bolt, a pull rope fixed at both ends to said carriage, a plurality of pulleys continually guiding said rope on a tortuous path, and a doctor holder attached to several sections of said rope moving in the same direction, contacts on the switch disc cooperating with the cams on said pull aggregate to close the circuit of the third motor and stop this motor after said disc has performed rotary movement determined by the position of said contacts and by the number of said cams, to determine the number of to and fro movements of the doctor holder.

8. A stencil printing machine as specified in claim 1, in which the machine comprises a printing table, a pasting apparatus, a pressure cylinder, a washing apparatus, and a drying apparatus all arranged in the path of travel of the endless printing support, and a heating plant adapted to feed heating medium through said printing

table, pasting apparatus, pressure cylinder, washing apparatus and drying apparatus.

9. In a stencil printing machine as specified in claim 1, a pasting apparatus, comprising a multipartite ribbed body adapted to apply stripes of paste on to the printing support, a paste feed roll, said ribbed body and said paste roll frictionally driven by said printing support, a squeegee roller bearing on said paste feed roll to determine the amount of paste fed, and a pressure cylinder adapted to press the paper web on to the pasted printing support, the ribs on said ribbed body being of such width and so spaced that the pasted stripes remain separate even after pressure has been excited by said pressure cylinder.

10. In a stencil printing machine as specified in claim 1, said washing apparatus for the printing support, comprising a container for hot water, brushes rotating partly submerged in the water 20 in said container, laterally reciprocatable strippers mounted above said brushes, and counter pressure rollers cooperating with said brushes and strippers to brush and scrape the printing support.

25 11. In a stencil printing machine as specified

in claim 1, means for fixing the stencils, comprising front and rear bars, front and rear riders adapted to fix said stencils to said bars, abutment bolts on said stencils, the front riders adapted to engage behind the abutment bolts on said stencils, the front bars serving as abutments for the printing table, and hand operated screws on the front riders adapted to press tightly against said front bars, and laterally adjustable abutment bolts on the rear riders adapted to laterally secure the rear ends of the stencils. 5

12. A stencil printing machine as specified in claim 1, in which the driving motors, the controlled gear, the toothed wheel, the doctor mechanism and the catch are controlled by switches 15 in a secondary circuit.

13. In a stencil printing machine as specified in claim 1, means for raising and lowering the stencils comprising stencil holding bars and a rod system connecting said bars with the toothed 20 wheel, the switch disc being only operative when the stencil holding bars are in their extreme positions to switch off said auxiliary motor and switch on the third motor.

JOSEF KESSEL. 25
